DESIGN FOR A GEARING HOBING MACHINE

Anthony J. Vasselli, Newark, N. J.

Application January 6, 1943, Serial No. 109,211

Term of patent 14 years

To all whom it may concern:

Be it known that I, Anthony J. Vasselli, a citizen of the United States of America, residing at Newark, county of Essex, State of New Jersey, whose post-office address is 46 Clinton St., Newark, N. J., have invented a new, original, and ornamental Design for a Gear Hobbing Machine, of which the following is a specification, reference being had to the accompanying drawings, forming part thereof.

Figure 1 is a front elevational view of a gear hobbing machine, showing my new design.

Figure 2 is an end view of the same.

Figure 3 is a plan view thereof with the gear train cover removed.

I claim:

The ornamental design for a gear hobbing machine, as shown.

ANTHONY J. VASSELLI.
